UNITED STATES PATENT OFFICE.

HARRY E. KERR, OF CLEVELAND, OHIO, ASSIGNOR TO THE CLEVELAND GAS BURNER & APPLIANCE COMPANY, OF CLEVELAND, OHIO, A CORPORATION OF OHIO.

GAS BURNER.

Application filed June 17, 1924. Serial No. 720,558.

To all whom it may concern:

Be it known that I, HARRY E. KERR, a citizen of the United States, residing at Cleveland, in the county of Cuyahoga and 5 State of Ohio, have invented certain new and useful Improvements in Gas Burners, of which the following is a specification.

My invention relates to an improvement in gas burners and more particularly an improvement in a gas burner of the type disclosed in Letters Patent of the United States, issued to W. J. Barber, No. 1,267,355 in which two streams of gas are commingled and caused to burn without initial admixture with air. My present object is to provide an effective burner in which separate streams or jets of gas are brought into confluence at converging angles together with separate streams of air to promote perfect combustion under either low or high gas pressure conditions, to prevent back-firing under a low or fluctuating gas pressure, and to produce a spreading flame which may be readily controlled and efficiently applied 20 in restricted or confined spaces. To attain my general object I provide a burner body having reversely-inclined burner nozzles which are particularly constructed to discharge attenuated streams or jets of gas 25 into confluence with considerable force so as to spread the gas and produce an ovoidal body of flame, the nozzles being also particularly constructed to permit the gas streams to entrain just the right amount of 30 air to maintain a sheath of flame around each jet or stream of gas under high-pressure operating conditions and also to promote a proper mixture of gas and air and a constant flame without back-firing under 35 low-pressure conditions.

My conception involves the use of relatively small nozzles in which the respective air and gas passages are definitely proportioned to permit the gas to issue with 40 considerable velocity so that the cores of the converging streams will strike each other unburnt and only the outer sheath of gas and entrained air will flame or burn from the mouth of each nozzle to the point of 45 confluence. The unburnt core of gas in forcibly striking a similar core of gas at a converging angle intermingles and spreads in ovoidal form, and the necessary additional volume of air to create perfect 50 combustion and an ovoidal body of flame is

drawn into the area of confluence from the surrounding space between and above the nozzles. The flame produced is orange blue in color, using either natural or manufactured gas, and the height of the ovoidal body of blue flame varies from four to seven inches according to the gas pressure. In this way a horizontally-elongated body of flame may be produced which will not be too high to prevent its use in fire pots of restricted height, and an intense heating effect is obtained within a small area, especially when two or more pairs of such nozzles are closely grouped as herein illustrated. A further object is to provide a cast-iron or aluminum manifold having inclined burner nozzles detachably affixed thereto, the nozzles being of brass or other non-corrosive metal and formed with relatively small gas orifices, so that corrosion cannot take 60 place to change the size or shape of the gas orifices and affect burning operations, especially after the burner has been in use for 65 a long period of time. The nozzles are 70 also grouped in a particular way to promote instant ignition and to constantly maintain burning of the gases at all of the confluent places in the burner, and there are other details of construction which embody other objects as will hereinafter more 75 fully appear in the detailed description of the invention.

In the accompanying drawings, Fig. 1 is a top view of a circular burner body embodying my invention, and Fig. 2 is a sectional view of the same burner on line 2—2 of Fig. 1. Fig. 3 is a sectional view of the burner body lengthwise of one of its protuberant portions and showing two nozzles seated on the inclined faces thereof. Fig. 4 is a top view of a burner having six sets of inclined nozzles, each pair of opposed nozzles which bring gas streams into confluence being shown slightly offset axially. Fig. 5 is a side view of the burner shown in Fig. 4 and Fig. 6 is a top view of a pair of offset nozzles in action.

As exemplified in Figs. 1 to 3 of the drawings, one form of the invention comprises a hollow ring or circular body 2 having an intake extension 3 at one side and a plugged opening 4 diametrically opposite intake 3. The top of body 2 is provided with a series of protuberances or raised portions 5 at uniformly spaced radial places, and 105

these protuberances 5 are rounded on top and have their opposite ends flattened in reversely inclined planes, the angle of inclination of each face 6 being approximately 45° to a horizontal plane. The successive protuberances 5 and their flat inclined end faces 6 are also arranged so that the flat surfaces will face each other in pairs on lines parallel with a radial line of the circle. Thus, 10 each pair of opposed faces 6—6 are reversely inclined, and where four round protuberances 5 are used upon a ring a series of short burner nozzles 7—7 may be mounted upon a circular body 2 so that separate 15 pairs of nozzles will extend upwardly and directly toward each other in reversely-inclined converging relation at four sides of said body. Fig. 3 discloses that each protuberance 5 is adapted to support two nozzles 7 in open communication with a single gas pocket 5', and that the two nozzles are inclined at right angles away from each other, but each nozzle is also inclined upwardly in a straight line toward a corresponding nozzle on an adjoining protuberance 5 on circular body 2, as shown in Fig. 2. In a squared arrangement of nozzles 20 eight tubes are supported in pairs upon the body so that eight streams or jets of gas mixture are brought into confluence at four 25 equally distant places from the center of the open circular body, whereby the gases brought into confluence are caused to spread radially of the circle to provide four radial sheets of flame of oval form substantially 30 as indicated in dotted lines in Fig. 1.

Each nozzle 7 is formed with a screw-threaded base portion 8 to permit it to be screwed into a screw-threaded opening 8' 40 formed centrally within each flat inclined face 6, and a flattened enlargement 10 permits a wrench to be used in attaching and removing nozzle. A very small gas orifice 9 is bored centrally within a cross wall in 45 the lower end of the tube, and a larger bore 11 extends outwardly therefrom to the upper end or mouth of the nozzle. One or more lateral air intake openings 12 are made in the side of the tube in substantially the 50 same plane as the bottom of bore 11 and the outlet end of orifice 9, so that the fine stream or jet of gas issuing through orifice 9 will entrain a small amount of air through opening 12 and bore 11 and effect a partial 55 mix with a part of the gas stream to produce partial combustion opposite the mouth of the tube. The pressure is usually such that the main stream of gas from each orifice is jetted with considerable force 60 axially—through bore 11 into the open beyond the mouth of the nozzle so that the main admixture of gas and air to promote complete combustion is effected outside of each pair of reversely-inclined nozzles 7. An ovoidal sheet of flame is thereby

produced radially in respect to the center of circular body 2, and in a squared arrangement of nozzles as delineated in Fig. 1, there will be four oblong sheets of flame at right angles to each other and the inner 70 edges of these sheets come close enough under full pressure to permit rapid ignition of all when any one of the four is ignited. When the gas is under full pressure these four sheets may also merge at their tops and 75 form a single large body of flame which will give an intense heating effect in a localized area above the open center of the burner.

Circular body 2 is preferably made of 80 cast-iron or aluminum and the nozzles may be made of brass or an alloy which will not corrode readily, the purpose being to prevent clogging or change in size of the gas orifices which must be very small in diameter and remain unobstructed to produce the desired jetting, mixing and burning effects. The angular setting of the tubes must also be accurately effected to obtain the best results, and body 2 is therefore formed with 85 separate protuberances 5 having flat inclined ends 6 to permit the screw-threaded openings 8' to be properly formed therein at the correct angle so as to seat and relate each 90 pair of co-acting tubes at the desired inclination. Other factors to consider are the spacing or distance between the nozzles, the length of the nozzle, and the kind of gas being used. The flow of gas and the pressure is also controlled by a suitable valve, 95 not shown, but understood to be used according to common practice, and when the gas pressure is low or turned down to the maximum a tip of blue flame will burn at the mouth of each nozzle without backfire and with a minimum consumption of gas, and when turned on more fully or with full force the gas is jetted from each nozzle in sufficient volume and at such velocity that 100 two converging streams of gas strike and mix and spread before igniting entirely and in so doing draw in air in sufficient volume from the surrounding space and around the nozzles to constantly maintain a sheet of flame of considerable width and height. 105 The air entrained through the nozzles maintains a thin sheath of blue flame around each core of gas jetted from each nozzle, but the main flame is maintained by the larger volume of air drawn in from the open space above the burner and mixed with the gas after the converging jets of gas meet and strike each other with considerable velocity and spread upwardly and laterally in a broad thin sheet. The flame is orange 110 blue in color with both natural gas and artificial or manufactured gas.

A different grouping of the nozzles may be effected without departing materially from the general scope and purpose of the 115 120 125 130

invention set forth herein. Thus in Fig. 4 I show a circular body 2' having six sets of nozzles 7' arranged at equally distant radial places in the circle. In this burner 5 the nozzles of each set are also staggered or offset axially in respect to each other, instead of being axially co-incident as shown in Fig. 1, the purpose being to cause the 10 separate jets of gas to strike each other with glancing effects, see Fig. 6, thereby producing a spreading sheet of flame obliquely or tangentially to the circle instead of radially as occurs when the axes of the two jets are co-incident. To explain further, in 15 a large circular burner for a round fire box the radial distance from each pair of nozzles to the center of the burner may be greatly in excess of the width of the sheet of flame produced by that pair of nozzles, and in 20 order to avoid separate pilot lights for each set of nozzles, it is desirable that the sheet of flame produced by one set of nozzles may be turned obliquely or at a tangent to the circle so that when it is ignited it will in turn 25 quickly ignite the gas issuing from the next adjoining set of nozzles and so on around the circle, as indicated by the dotted arrows in Fig. 4.

What I regard as my invention and desire 30 to claim, is:

1. A gas burner for heating purposes adapted to produce complete combustion uniformly with various kinds of gases under varying or fluctuating gas pressures, 35 comprising a hollow gas-distributing body having a pair of reversely-inclined nozzles adapted to bring separate streams of gas and air into confluence; each nozzle being a separate removable member having a base portion formed with an enlarged gas-intake recess terminating in a small and short axial 40 gas orifice adapted to promote high velocity of discharge of the gas through the nozzle, and a lateral air intake opening in the base portion of said nozzle leading to the outlet end of said orifice.

2. A gas burner for heating purposes adapted to produce perfect combustion equally with either natural or manufactured 50 gas or such gases mixed, at either low or high gas pressures, and under fluctuating pressures, comprising a hollow burner body having screw-threaded openings therein ex-

tending upwardly toward each other at substantially right angles, and separate nozzles screwed into said openings having enlarged gas intakes terminating in short axial gas orifices and formed with side air intake openings in their base portions in substantially the same plane as the outlet 60 end of the orifices adapted to bring separate streams of air and gas into confluence.

3. A gas burner for heating purposes, adapted to produce perfect combustion equally with various kinds of gases under 65 varying or fluctuating gas pressures, comprising a hollow gas-distributing body having integral protuberances provided with reversely-inclined flat faces formed with screw-threaded openings, and a pair of gas 70 nozzles removably screwed into openings at right angles toward each other to permit separate streams of gas to be jetted into confluence with flat spreading effect, said nozzles having screw-threaded base portions 75 formed with enlarged intakes terminating in relatively short gas orifices in their base portions and lateral intake openings at their sides in substantially the same plane as the outlet end of said orifices to permit a small 80 amount of air to be entrained through each nozzle with each stream of gas.

4. A gas burner, comprising a pair of reversely related nozzles adapted to project separate streams of gas into confluence, said 85 nozzles being axially offset in slight degree to effect glancing impact of said streams of gas and a spreading sheet of gas obliquely to the stream line.

5. A gas burner comprising an unobstructed commingler tube having a cross port forming an air inlet thereto and a gas jet aperture in the surface of said cross port aligned with said commingler tube, said air inlet port being restricted in area to retard 95 the rate of flame propagation in the mixture whereby said tube will be swept free from all flame at mixture velocities obtainable with normal gas pressure.

6. In a gas burner, a pair of opposed jet 100 tubes in slightly offset relation, whereby the resulting flame extends at an oblique angle to said jets.

In testimony whereof I affix my signature.

HARRY E. KERR.

DISCLAIMER

1,560,248.—*Harry E. Kerr, Cleveland, Ohio. GAS BURNER.* Patent dated November 3, 1925. Disclaimer filed May 23, 1931, by the assignee, *The Barber Gas Burner Company*.

Hereby enters this disclaimer to said claim 5 of said Letters Patent, which is in the following words, to-wit:

“5. A gas burner comprising an unobstructed commingler tube having a cross port forming an air inlet thereto and a gas jet aperture in the surface of said cross port aligned with said commingler tube, said air inlet port being restricted in area to retard the rate of flame propagation in the mixture whereby said tube will be swept free from all flame at mixture velocities obtainable with normal gas pressure.”
